United States Patent Office

Des. 174,019
Patented Feb. 15, 1955

174,019

DRESS OR SIMILAR ARTICLE

Oleg Cassini, New York, N. Y., assignor to Oleg Cassini, Inc., New York, N. Y.

Application October 22, 1954, Serial No. 32,776

Term of patent 3½ years

(Cl. D3—26)

Fig. 1

To all whom it may concern:

Be it known that I, Oleg Cassini, a citizen of the United States of America, residing in New York city, county of New York, and State of New York, have invented a new, original, and ornamental Design for a Dress or Similar Article, of which the following is a specification, reference being had to the accompanying drawing, forming part thereof.

Fig. 1 is a front view of a dress or similar article, showing my new design.

Fig. 2 is a rear view thereof.

I claim:

The ornamental design for a dress or similar article, substantially as shown.
